UNITED STATES PATENT OFFICE.

EUGENE A. CROWE, OF BROOKLYN, NEW YORK, ASSIGNOR TO THE
E. S. HIGGINS CARPET COMPANY, OF NEW YORK, N. Y.

DESIGN FOR CARPET.

SPECIFICATION forming part of Design No. 28,252, dated February 1, 1898.

Application filed December 23, 1897. Serial No. 663,265. Term of patent 31 years.

To all whom it may concern:

Be it known that I, EUGENE A. CROWE, a citizen of the United States, residing at Brooklyn, in the county of Kings and State of New York, have invented and produced a new and original Design for Carpet, of which the following is a specification, reference being had to the accompanying drawing, forming a part thereof, which represents a face view of a carpet in which my new design is embodied.

The design relates to a design to be worked into or upon surfaces such as carpets and similar fabrics; and it consists of the novel combination of the figures, as herein shown and claimed.

A foliate figure A is a prominent feature of the design, and comprises a compound curved stem and leaves and sprays carried by the stem with a feathery effect, the leaves and sprays appearing at the ends as well as at the sides of the stem. The figure A is associated with scrolls B and C. The scroll B extends from one end of the foliate figure A and com-

prises a curved body and a spiral return. The return portion of the scroll B is similar to scroll C, which connects with the opposite end of the foliate figure A.

Groups D and D' of foliate figures are arranged at the sides of the scroll B, each group consisting of a number of stems and leaves in feathery arrangement upon the stems, and similar stems E and E' are arranged at each side of the scroll C. A scroll F is carried from the leaved stem E, extending at one side of the main foliate figure A, and at the opposite side of this figure a double scroll G is arranged to extend, one member toward the leaved stem E' and the other toward the group D'.

I claim—

The design for carpet herein shown and described.

EUGENE A. CROWE.
